ATTPYS.

UNITED STATES PATENT OFFICE.

WILLIAM B. LARKINS, OF SAN RAFAEL, CALIFORNIA.

DESIGN FOR A CORNER-PIECE FOR VEHICLE-TOPS.

59,362.

Specification for Design.

Patented Oct. 11, 1921.

Application filed June 18, 1921. Serial No. 478,748. Term of patent 7 years.

To all whom it may concern:

Be it known that I, WILLIAM B. LARKINS, a citizen of the United States, residing at San Rafael, in the county of Marin and State of California, have invented a new, original, and ornamental Design for a Corner-Piece for Vehicle - Tops, of which the following is a specification, reference being had to the accompanying drawing, forming part thereof.

Figure 1 is a front view of a corner piece for vehicle tops, and Figs. 2 and 3 are end and rear views respectively of my improved corner piece for vehicle tops, showing my new design.

I claim:

The ornamental design for a corner piece for vehicle tops, as shown.

Dated June 11, 1921.

WILLIAM B. LARKINS.
